UNITED STATES PATENT OFFICE.

FRANK V. LANHAM, OF DALLAS, TEXAS.

PAVEMENT.

Application filed January 7, 1927. Serial No. 159,514.

This invention relates to new and useful improvements in pavements.

It is well understood that horse-drawn vehicles do not create such severe and deteriorating conditions upon roadways as are imposed by motor vehicle traffic and the present invention has to do with a pavement designed, laid, and composed of materials capable of withstanding such motor vehicle traffic and the loads incident thereto.

One object of the invention is to provide a pavement in which the rigidity, solidity, and strength of concrete pavement will be obtained.

Another object of the invention is to provide a pavement in which the major portion of the investment is not subject to replacement, thus requiring only a minor financial investment in that portion of the pavement which is subject to repair.

It has been the practice in the laying of pavements to partially imbed small stones or rocks in the surface of a cement course and to utilize the upwardly projecting portions of the stones to bond a top layer onto the cement course. However, the top course has always been given considerable thickness and is known as the "wear layer" of the pavement. The top, or wear layer, is more or less expensive to construct and replace.

A particular object of the invention is to provide a wear layer composed of stones or rocks, partially imbedded in the surface of the course on which the wear layer is superimposed, whereby said stones or rocks will take the wear directly and substantially.

A further object of the invention is to fill the voids or interstices between the projections of the stones with a filler having its upper surface substantially flush with the highest points of the projecting stones, whereby a smooth and pleasing surface is presented. It is preferable to use a bituminous filler which not only makes a smooth and pleasing appearance, but serves to compensate expansion and contraction, and tends to heal or fill cracks.

It is especially the aim of the invention to employ irregular shaped stones or crushed rock, which when imbedded in close relation in the supporting course, will, owing to their irregularities, overhang and interlock with each other, thus tending to prevent relative vertical displacement, thereby making for a more permanent structure.

A construction designed to carry out the

invention will be hereinafter described, together with other features of the invention.

The invention will be more readily understood from a reading of the following specification and by reference to the accompanying drawings, in which an example of the invention is shown and wherein:

Fig. 1 is a transverse sectional view of the sub-grade upon which the concrete foundation has been laid,

Fig. 2 is a similar view with the rocks or stones spread on the foundation and ready for imbedding,

Fig. 3 is a similar view showing the rocks imbedded to substantially half their diameter,

Fig. 4 is a similar view of the completed pavement,

Fig. 5 is an isometrical view of a portion of a pavement constructed in accordance with my invention and before the filler has been applied, and

Fig. 6 is a similar view after the filler has been applied.

In the drawings the numeral 10 designates the usual sub-grade, which is produced in accordance with the usual practice in this art. Curbs or binder walls 11 are provided along each side of the sub-grade, as is shown in Fig. 1. A concrete foundation 12, of such strength and thickness as to support the loads which the street or highway is to carry, is laid on the sub-grade 10 and may be reinforced with metal if desired. The ingredients and consistency of the foundation may vary in accordance with the specifications in accordance with which the pavement is to be built.

While the concrete foundation is "green" and prior to its initial set, a layer or covering of hard broken or crushed stones or rocks 13 is uniformly spread in close contact over the top surface of the foundation. It is preferable to use crushed stones of substantially uniform diameter, stones of approximately two inches in diameter having given satisfactory results; however, the invention is not to be limited to the size of these stones. It is highly desirable that stones or rocks of irregular shape be used so that when they are embedded, as is shown in Figs. 5 and 6, they will overhang or interlock, thus holding each other against relative vertical displacement. These stones are placed preferably in a single layer and as close together as is practical without piling one upon the

other. This layer of stones is then lightly tamped or rolled so that the stones will be imbedded in the "green" concrete to approximately one-half or more of their diameter, 5 whereby the upper half or portion of each stone will project above the top surface of the concrete foundation and the lower half thereof will be imbedded in said foundation. By this arrangement the stones will be securely anchored and fastened in the foundation when the concrete sets. When the stones 10 have thus been embedded in the green concrete those portions of the stones embedded in the concrete will be closely positioned to one another and, in some instances, they might be in actual contact. In actual practice, however, it has been found that the mortar of the concrete, being more or less plastic, finds its way between the surfaces 15 of juxtaposed stones so that instead of the stones actually contacting with one another they are somewhat spaced apart by an intervening film of the mortar.

It has been the practice in building pavements to use small stones or crushed rocks 25 as a bonding means between two courses, but such rocks or stones were not spread in close relation, but scattered and were covered with a top layer or course several inches thick.

30 It will be seen that the projecting upper portions of the stones will provide a substantially continuous layer which will be rough and angular and composed almost entirely of hard, durable wear-resisting rocks.

35 After the concrete has set, the surface of this wear layer is swept clean to remove loose particles of stone, dirt, or other foreign materials; and there is then applied to the said layer a filler 14 to fill the interstices or

40 voids flush with the highest points of the projecting portions of the stones. While the highest points of the stones may be covered by the filler, particularly where it is fluent, only enough filler is applied to fill the voids

45 and produce a surface substantially flush with the highest points of the stones. By this method only about one-tenth the quantity of material is used for the filler, per square yard, as is used in the usual top layer which

50 is bonded to the under layer by stones, such as is shown in the patents to Lake 507,683, issued October 31, 1893, and Warren 916,070, issued March 23, 1909. It is preferable to use a bituminous composition which has been brought to the proper temperature to insure an even distribution and in such quantity that after being loaded with fine mineral aggregate, will completely fill all interstices and surface voids.

55 60 After this step, clean, coarse sand, stone screenings, or other suitable material in sufficient quantity is spread over the layer 14. The surface may be lightly rolled or otherwise treated in accordance with the practice in this art.

A pavement constructed in accordance with my invention will have many advantages and will tend to eliminate most of the difficulties and causes of failure heretofore encountered in the construction of such 70 pavements as are now in common use. The wearing surface of the pavement constructed in accordance with my invention will present to traffic a wearing surface or layer composed of hard, durable and tough 75 stones, firmly anchored against creeping or lateral displacement. The weight of traffic will at all times rest directly on the tops of the stones rather than upon the plastic 80 filler, the stones being in such close relation that several will sustain the load of the average motor vehicle tire, thus overcoming the disastrous results which occur where the load is carried by a bituminous top 85 layer. My pavement will possess a great 90 advantage over concrete pavement, as ordinarily constructed, because the mortar which necessarily comes to the surface of a concrete pavement, due to the sinking of the coarse aggregate therein, is not capable of 95 withstanding abrasion, but functions merely as a bond or cement, and in my pavement there is no such top mortar exposed to wear.

A pavement constructed in accordance with my invention, will, it is believed, 100 possess greater solidity, continuity and cohesion than those pavements in which two dissimilar layers are merely bonded together by stones or rocks. It will, of course, be apparent that the bituminous filler will add 105 to the life of the pavement because it will protect the projecting portions of the stones from being broken off, cracked, or chipped. The stones overhanging and interlocking, as is shown in Figs. 5 and 6, will not be easily 110 dislodged, yet they will sustain the maximum wear and tear upon the pavement.

This application is filed as a continuation in part of application, Serial No. 144,794.

Various changes in the size and shape of 110 the different parts, as well as modifications and alterations, may be made within the scope of the appended claims.

What I claim is:

1. A pavement consisting of a concrete 115 foundation, a wear layer of relatively large stones or rocks embedded partially in said foundation with their upper portions protruding from said foundation in close relation to form a wearing surface whereby a plurality of juxtaposed stones or rocks will substantially simultaneously engage the thread of a vehicle wheel passing over the same, and a filler deposited in the voids between the portions of the rocks or stones 120 protruding above said foundation.

2. A pavement consisting of a concrete 125 foundation, a wear layer of relatively large stones or rocks embedded partially in said foundation with their upper portions pro-

truding therefrom to form a wearing surface, the embedded portion of each stone or rock having an interlocking relation with another stone or rock positioned next adjacent thereto, and a filler deposited in the voids between the protruding upper portions of the stones or rocks.

3. A pavement consisting of a concrete foundation, a wear layer of relatively large stones or rocks embedded partially in said foundation with their upper portions protruding therefrom to form a wearing surface, the embedded portion of each rock being closely positioned to and adapted to receive lateral support from the stones or rocks surrounding the same, and a filler deposited in the voids between the protruding upper portions of the stones or rocks.

4. A pavement consisting of a concrete foundation, a wear layer consisting of a single course of relatively large stones or rocks partially embedded in said foundation with their upper portions protruding from said foundation in close relation to form a wearing surface, the embedded portion of each stone or rock having an interlocking relation with another stone or rock positioned next adjacent thereto and the embedded portions of each rock being closely positioned and adapted to receive lateral support from the stones or rocks surrounding the same, and a filler deposited in the voids between the protruding upper portions of the stones or rocks.

In testimony whereof I affix my signature.
FRANK V. LANHAM.
